(57) **CLAIM**

The ornamental design for a dishwasher sprayer, as shown and described.

DESCRIPTION

FIG. 1 is a top perspective view of a dishwasher sprayer showing our new design;

FIG. 2 is a top perspective view of the dishwasher sprayer in FIG. 1;

FIG. 3 is a bottom perspective view thereof;

FIG. 4 is an enlarged front view thereof;

FIG. 5 is an enlarged rear view thereof;

FIG. 6 is a right side view thereof;

FIG. 7 is a left side view thereof;

FIG. 8 is a top view thereof; and,

FIG. 9 is a bottom view thereof.

The broken line dishwasher rack illustrates the environment for the dishwasher sprayer. The remaining broken lines illustrate portions of the dishwasher sprayer. Neither of the broken line disclosures form part of the claimed design.

1 Claim, 9 Drawing Sheets

Related U.S. Application Data

continuation of application No. 16/232,647, filed on Dec. 26, 2018, now Pat. No. 11,006,813.
